UNITED STATES PATENT OFFICE.

CHARLES E. MORRIS, OF LANE, KANSAS.

THROTTLE-LEVER-OPERATED CONTROLLER AND ACCELERATOR.

1,103,151.

Specification of Letters Patent. Patented July 14, 1914.

Application filed June 28, 1912. Serial No. 706,534.

To all whom it may concern:

Be it known that I, CHARLES E. MORRIS, a citizen of the United States of America, residing at Lane, in the county of Franklin, 5 and State of Kansas, have invented certain new and useful Improvements in Throttle Lever-Operated Controllers and Accelerators; and I do hereby declare that the following is a full, clear, and exact description 10 of the invention, such as will enable others to make and use the same, reference being had to the accompanying drawing, forming a part of this specification.

The object of the invention is, First,—to afford a safe action of a controller to the throttle of a gas engine in motor vehicles and remove the danger which accompanies misuse of the accelerator. Second:—to assure the automatic closing of the throttle 20 when opened accidentally. Third:—to govern the extent of opening of the throttle in the application of power to the foot pedal, and fourth:—to enable the position of the throttle to remain unchanged when opened 25 to a required extent, unaffected by the spasmodic running of the engine due to the uneven condition of the road.

The invention consists in the novel construction and combination of parts such as 30 will be first fully described and then specifically pointed out in the claim.

In the drawings, Figure 1, is a side view of the invention and a vertical section of a flooring supporting the same. Fig. 2, is a 35 plan view taken on the line $\alpha\alpha$ on Fig. 1. Fig. 3, is a direct front view of the operating bar, and Fig. 4, is a broken view of the invention as seen in Fig. 1, showing a modification.

40 Similar numerals of reference indicate corresponding parts in all the figures of the drawings.

Referring to the drawing in detail, 5 indicates a portion of a flooring forming a 45 part of the body of a motor vehicle to the lower surface of which is secured rigidly the horizontal upper portion of a vertically positioned supporting plate 6, this plate is provided with horizontal extensions or lugs 50 7, upon a line with said upper portion of said plate said lugs being secured to the flooring 5, by means of screws 8. The lower portion of plate 6, extends downwardly the requisite distance and upon one side of the 55 plate adjacent said lower portions is a boss 9, integral with said plate.

10, indicates a rotary ratchet disk or segment plate upon the inner surface of which at the axes of motion of which plate is a hub 11, through which hub extends a pivot bolt 12, which bolt extends within the boss 9. In the peripheral portion of the segment plate are a series of ratchet teeth 14, extending as shown, a portion of the distance of the arc of the circle of the segment plate. 60

15, indicates the throttle valve operating rod, the inner end of which rod is forked, and said forked portions extended on both inner and outer surfaces of the segment plate and pivotally connected at 15^x to the lower portions of the segment plate, the outer end of the rod being connected with the valve not shown in the ordinary manner. Upon the rod 15, a considerable distance 70 outwardly from its pivotal inner end is a clamp 16, having an upward extension or lug 17.

18, indicates an air cylinder or dash pot, having heads 19 and 20, at its respective 80 forward and rear ends. A short portion 18^x, of the cylinder extends beyond the head 19. Through the lug 17, on the clamp 16 extends a U shaped link 21, the ends of which link are rigidly connected with outer surface of said extended portion 18^x, of the cylinder 18. Within the cylinder 18, is a piston 22, with which piston is connected one end of a piston rod 23, the other end of which rod extends rearwardly and loosely 90 through the head 20, of the cylinder 18, and is pivotally connected at 24, with the outer end of a post 25, which is located on the same side of the supporting plate 6, having the boss 9, and at the lower and forward end portion. 95

26, indicates a bell crank lever mounted on the pivot 12, and upon the inner surface of which lever is a short hub 27, which extends around the pivot 12, and separates the said lever from contact with the segment plate 10. One arm 28, of the bell crank lever is extended rearwardly nearly three times the length of the short arm 29, which extends in an upward direction a short distance. With 100 this short end 29, of the lever is pivotally connected at 31, the rear end of a flat bar 32, which extends forwardly a short distance.

33, indicates a vertical bar or bracket having flanges at its upper ends which flanges 110 are secured by the screws 34, to the lower surface of the flooring 5, its lower end ex-

tending downwardly to a position horizontally in line with the outer surfaces of the arms 28, and 29, of the bell crank lever 26, and outwardly from a vertical line passing through the valve operating rod 15. With the lower end of the bracket 33, is pivotally connected at 35, one end of a coiled spring 36, the other end of which spring is pivotally connected with the forward end of the bar 32. In the flooring 5, in a vertical line with the inner surface and rear end portion of the arm 29, of the bell crank lever 26, is a vertical opening 37. In the upper surface of the flooring 5, is a plate 38, extending over said opening 37, and in which plate is an opening 39, registering with the opening 37. In the openings 39 and 37, is loosely fitted the operating pedal bar 40, in which bar at a point approximately equidistant from its ends is a transverse opening 41. Upon the upper end and outer side portion of bar 40, which extends normally a short distance above the line of the upper surface of the flooring 5, is a foot lever 43, pivoted at 44, to the said bar 40, said upper end portions of the bar being curved or rounded. Upon the upper end of the lever 43, is a foot rest 45. The lower end of the lever 43, from the pivot 44, is made narrow in width, approximately one-half the width of the said bar 40, so as to obtain a forward and rear play within the slot 37. The lower end of the lever 43, at a point directly opposite the line of the lower surface of the flooring 5, is bent at right angles and extended rearwardly to and in contact with the forward portion of said opening 37, to form a catch 46.

47, indicates a pivot post on the same side of the supporting plate 6, having the boss 9, and located near the upper portion of said plate a short distance forwardly of the vertical operating bar 40. Upon outer end of the pivot post 47, is a dog 48. This dog consists of a flat plate having its forward end pivoted to the post 47, and its rear end curved forwardly and downwardly from the line of its upper surface in the arc of a circle as at 49, and also curved rearwardly and downwardly from the line of the forward end of said plate as at 50, the curved lines 49 and 50, meeting at a point as at 51. The rear end portion of the plate or dog 48, extends rearwardly within the opening 41, of the operating bar 40.

52, indicates a pawl which is located in the lower portion of the opening 41, in the bar 40, and pivoted thereto at 53, at a point a short distance below a horizontal line extending through the pivot post 47, supporting the dog 48. The upper surface of the dog 52, is curved in the arc of a circle and upon the same line of curvature as the curved portion 49, of the dog 48, within

65 which curved portion of the dog the upper

surface of the dog is operably received in a full upward movement of the operating bar 40. The forward end of the pawl 52, engages with the ratchet teeth 14, in the segment plate 10, in the manner further described. The rear end of the pawl 52, is extended rearwardly a short distance from the pivot 53, and form a weighted portion to the pawl, and tend to overcome the weight of the forward end of said pawl. Said pawl is held in its normal position by means of a transverse lug 54, secured to the lower surface of said rear end of the pawl, and bears upon the rear surfaces of the plates 41, and 42, of the bar 40.

In the rear end portions of the long arm 28, of the bell crank lever is a longitudinal opening or slot 55, short in length. In the lower end and outer side portion of the portion 42, of the bar 40, is a pivot 56, which extends outwardly within the slot 55.

In the operation of the controller power is applied by the action of the foot to the foot plate 45, forcing downwardly the operating bar 40, which moves in a path tangential to the periphery of the ratchet plate or disk 10, and expanding the spring 36, on the short arm of the bell crank lever 26. This action moves the catch 46, below the opening 37, in the flooring 5, and the lever 43, moves rearwardly into the dotted position seen in Fig. 1. In the same downward movement of the bar 40, the pawl 52, which moves downwardly with the bar 40, leaves the engaging surface 49, of the dog 48, the forward end of the pawl engaging with the first ratchet tooth lowest in position in the segment plate 10, partially rotating the segment plate and at the same time moving forward the valve operating rod 15, a proportionate distance, hence admitting the requisite supply of fuel to the engine for its incipient or starting movement, a little above the slowest degree of speed of the engine.

Upon releasing the pressure of the foot from the foot plate 45, the parts described automatically return to their normal position within the interval of time required for the piston 20, in the cylinder 18, to resume its normal position. In order to accelerate the movement of the valve operating rod 15, the movement just described must be repeated in order to open the throttle its full extent, but in each instance the throttle is closed automatically upon the release of the foot from the foot lever 43. In these repeated movements the successive engagement of the pawl with the successive ratchet teeth, the dog alternately engages with the ratchet teeth in succession holding the segment plate until the pawl renews an engagement with a ratchet tooth above the first engaged.

Each engagement of the pawl 52, with the

ratchet teeth is a full downward movement of the operating bar 40, so that while the foot remains on the foot plate 45, the throttle is in a fixed position unaffected by the 5 spasmodic action of the engine in moving over rough roads, the hands of the operator being always free to control the movement of the vehicle.

The invention has sought to do away with 10 the two operations incident to two pedals, for the reason that in most cases the danger arises in motor vehicles when the attention of the operator is given to the brake and the cut off or throttle valve should then self act. 15 I have shown on Fig. 3, a construction in which the foot lever 43, is dispensed with. In this construction the upper portion of the operating lever 60, is bent rearwardly from 20 a vertical line passing through the lever forming the forward shoulder 61, and the rear shoulder 62. The opening 63, in the flooring is made of increased proportions in 25 the longitudinal direction of the flooring so as to permit a forward and rear movement of the bar 60, therein. Upon the upper end 30 of the bar 60, is a fixed foot plate 64. The remaining parts of the controller are the same as in Fig. 1. Downward pressure on the plate 64, is accompanied with a forward 35 movement of the bar 60, which causes the pawl and dog to engage alternately with the segment plate 10.

The invention is applicable for other uses than for the control of throttle valves and 35 while applicable to give increased efficiency to the motor vehicle, may be applied wher-

ever its utility is found servicable with such other modifications as are within the scope of the appended claim.

Having fully described my invention what 40 I now claim as new and desire to secure by Letters Patent is,

In valve controlling mechanism the combination with a stationary support having an opening therein of a vertically positioned 45 supporting plate secured to the lower surface thereof, a pivot post on said plate and a ratchet disk mounted rotatably on said post, a valve operating rod pivotally connected at one end with the said ratchet disk, a bell 50 crank lever mounted on said post having arms of diverse lengths, a coiled spring connected with the short arm of the lever at one end and with a suitable support on the lower surface of the said stationary support 55 at the other end, a pedal bar movable vertically in the opening in said stationary support and tangentially to the periphery of the ratchet disk, the long arm of the bell crank lever having a slot and a pivot on the lower 60 portion of the pedal bar engaging with said slot, a dog pivotally connected with the supporting plate for said ratchet disk engaging with said disk and a gravity pawl 65 on the pedal bar adapted to simultaneously remove the said dog in the upward movement of the pedal bar.
